JESSE V. MEISER, OF PACIFIC PALISADES, CALIFORNIA

PICTURE-EXHIBITING MACHINE

Application filed November 24, 1928. Serial No. 321,655.

This invention relates to an apparatus for winding upon and unwinding from reels a flexible connection or belt which is adapted to be used for displaying advertising, for displaying pictures mounted thereon, or for bringing progressively into view any other matter which can be inscribed upon, carried by, or make up a belt or other flexible connection.

10 Among the objects of the invention are to provide an improved automatic means for keeping the matter to be displayed continuously in motion so that all portions thereof will be progressively displayed in an advantageous manner at the desired rate of speed.

An important feature of the invention consists in an improved mechanism for causing the power of the motor to be shifted from the operation of one reel to that of the other reel, 20 so that one reel will be stopped and the other reel automatically put into motion at the proper times.

Other objects are to improve apparatus of the class to which the invention pertains with 25 respect to simplicity and durability and positiveness in operation.

Still other objects and advantages may hereinafter appear.

Referring to the accompanying drawings 30 which illustrate the invention,

Fig. 1 is a side elevation of the complete apparatus looking at the same from the side thereof from which the matter displayed is to be observed.

35 Fig. 2 is a plan view of the complete apparatus.

Fig. 3 is a vertical section thereof on line 3-3 of Fig. 1.

Fig. 4 is a vertical section of the clutch on 40 line 4-4 of Fig. 3.

Fig. 5 is an end elevation of Fig. 4.

Fig. 6 is an enlarged side elevation of the motion changing device.

Referring in detail to the drawings, the 45 main elements of the apparatus are the flexible connection or displaying belt 9 winding upon and unwinding from the spaced apart reels 10 and 11 which are respectively mounted upon vertical shafts 12 and 13 and move 50 the displaying section of said belt through

the exhibition case or compartment 14.

The operating means will now be described in detail. The motor 17 operates the primary driving shaft 18 upon which is secured a worm 19 that is in mesh with a relatively 55 large worm gear wheel 20. Said wheel 20 is secured to a main transmission shaft 21 which in turn has a pinion gear 22 secured to it, the latter gear being in mesh with gear teeth 23 formed on a continuously rotating clutch 60 member 24. On one side of said clutch member 24 is a cooperating clutch member 25, and on the other side thereof is a cooperating clutch member 26. To the cooperating clutch member 25 is secured a secondary transmitting shaft 27, and to the other cooperating clutch member 26 is secured a transmitting shaft 28. Said shafts 27 and 28 align with each other and have their adjacent ends in close proximity, thus providing a support 70 and bearing for the hub portion 30 of the middle clutch member 24.

In order to operate the clutch elements which have just been described, a clutch operating frame is provided, said frame consisting of the upright arms 31 and 32 which are respectively pivotally secured at their lower ends to the supporting feet or lugs 33 and 34. The upper ends of said upright arms 31 and 32 are pivotally connected to the ends of a 75 cross arm 35 having near its center an upwardly extending yoke 36 whereby said cross arm 35 is shifted back and forth by means of a crank 37 which forms a part of a shaft 38 operated by means described later. The 80 movements of arms 31 are controlled by a guide or bracket B (see Figs. 4 and 5) which is supported from standard S by means of arms T.

The upright clutch-shifting arm 31 is provided with a yoke 31^a which embraces a grooved hub 25^a with which the shiftable clutch element 25 is provided, and the upright arm 32 is provided with a yoke 32^a which cooperates with a grooved hub 26^a with which the clutch element 26 is provided. The central, continuously rotatable clutch element 24 is provided with holes 39 which are bored therethrough as well shown in Figure 4, and the movable clutch elements 25 and 26 are 100

provided with pins 40 adapted to enter said holes or seats 39 when the clutch is operated. To the shaft 27 is secured a collar 27^a, and a spiral compression spring 27^c around shaft 27 also cooperates with a like spring 28^c and collar 28^b at the other side of the clutch normally to hold the clutch in the neutral position shown in Fig. 4 wherein said springs 27^c and 28^c are extended to the limit of their resiliency.

Returning now to the shaft 38 which carries the clutch operating crank arm 37, said shaft 38 has fixed thereto a cam plate 45, said cam plate having at one side of said shaft a segmental portion 46, and at its other side an operating arm 47 which is actuated by a lever 48 pivoted between its ends to a supporting pivot 49 so as to operate in a vertical plane. The lower end of said lever 48 is positioned with a part 48^a thereof between a pair of yoke arms 50, and when said yoke is reciprocated, as will presently be described, said lever is caused to oscillate in such a manner that the upper end thereof sweeps back and forth across the free end of the operating arm 47 of cam plate 45. To said lever 48 is secured an overthrow spring 55, the straight upper end portion 55^a of said spring extending within a yoke or guide 56 carried by cam plate 45 in order to afford a lost motion operative relation between said spring and cam plate. Cam plate 45 is provided at one side with a stop shoulder 45^s which cooperates with a stop 80, and at the other side with a stop shoulder 45^t which cooperates with a stop 81.

Cam plate 45 is provided at one side of its operating arm 47 with a cam surface 47^a and at the other side of said arm with a cam surface 47^b, and the rounded upper end of the operating lever 48 sweeps across first one and then the other of these cam surfaces in operating said cam plate. The coiled lower portion of spring 55 is seated upon and secured to a stud 55^b which is carried by lever 48 a short distance above its supporting pivot 49. This arrangement of said spring, cam plate and lever causes a reverse throw to be given to said cam plate whenever the adjacent end of said lever clears the end of the operating arm 47.

Referring now to the means for reciprocating yoke 50 which has already been alluded to, said yoke 50 is held against rotation by a guide rail 60 and has a screw threaded connection with a screw shaft 61. Said screw shaft 61 has fixed thereto a sprocket wheel 61^a. Sprocket chain 64 engages said wheel 61^a and also engages sprocket wheel 65 on shaft 28.

The upright shaft 12 of reel 10 has fixed to it a bevel gear 12^a which is driven by a bevel gear 12^b fixed to shaft 28, and the other reel shaft 13 has fixed to it a bevel gear 13^a which is driven by a bevel gear 13^b fixed to shaft 27.

The exhibition case 14 may be shaped and

supported in any suitable manner in order to display to advantage the pictures or other matter carried by the sheet or connection 9. In the drawings said case 14 is shown supported by the top cross piece 70 of a frame having end pieces or uprights 71 and a base member 72. Said case 14 is secured to the lower side of top piece 70 by means of a spacing member 73 thus providing room for the top bearings 74 and 75 of reel shafts 12 and 13, in order to bring the sheet or connection 9 into proper alinement with the transparent face plate 76 of the casing 14. Said casing 14 is preferably tapered from front to rear as shown in Fig. 2 of the drawings, and has a reflecting inner surface in the contracted portion of which is located a lamp 77 adapted to illuminate the exposed portion of the connection 9.

In operation, the motor is started and kept running thus rotating continuously primary shaft 18 carrying worm 19 which meshes with worm gear wheel 20 fixed to main transmission shaft 21, said main transmission shaft 21, by means of its gear 22 rotates continuously the middle clutch member 24. Assuming said clutch member 24 to be engaged by the pins 40 of the left hand shiftable clutch member 25 as seen in Fig. 4, the operation of the motor will cause continuous rotation of the shaft 27, the latter shaft by means of gears 13^b and 13^a will rotate upright shaft 13 of reel 11 thus unwinding the sheet 9 from reel 10 and winding it upon reel 11. The rotation of reel 10 thus caused will also rotate reel shaft 12, its gear 12^a, gear 12^b and shaft 28. Shaft 28 through sprocket wheels 65, 61^a and sprocket chain 64 will rotate screw shaft 61. Such rotation of screw shaft 61 will move the member 50 mounted thereon, say toward the left as seen in Figs. 1 and 6. Continuous left hand movement of member 50 together with the lower end of lever 48 will cause the upper end of said lever 48 to move toward the end of the cam plate arm 47 until said arm reaches the left hand dotted position of Fig. 6 wherein the shoulder 45^s of the cam plate is brought into approximate engagement with the stop 80 at which time the upper end of lever 48 will free itself from the end of arm 47 and the spring 55 will thereupon give a sudden right hand overthrow movement to the cam plate thus bringing its right hand shoulder 45^t into contact with the stop 81. When this occurs said cam plate will by means of the shaft 38 to which it is fixed, and the crank arm 37 carried by said shaft, (see Fig. 4) actuate the cross bar 35 of the clutch shifting frame thus withdrawing the pin 40 of clutch member 25 from the central clutch member 24 and at the same time moving the pins 40 of the clutch member 26 into engagement with the central clutch member 24.

The upright shaft 12 of reel 10 has fixed to it a bevel gear 12^a which is driven by a bevel gear 12^b fixed to shaft 28, and the other reel shaft 13 has fixed to it a bevel gear 13^a which is driven by a bevel gear 13^b fixed to shaft 27.

The result of this movement will be to disconnect the continuously rotating clutch member 24 from shaft 27 and connect it with shaft 28 so that the motor will directly rotate shaft 28 and said shaft 28 will therefore be rotated in the reverse direction. Hence, as soon as this reverse movement of the cam plate 45 takes place the traveling member 50 begins to move in the reverse direction along 10 said screw shaft 61.

The various gears are of such arrangement and relative size that the screw shaft 61 will cause the traveling head 50 to actuate the cam plate 45, operate the clutch and stop 15 the rotation of one reel and start the rotation of the other when the proper time comes for doing so, that is to say, after the entire matter to be displayed has been run across the display casing.

20 I claim:

1. In a device of the class described, two reels in spaced relation to each other, upright reel shafts to which said reels are secured to rotate in a horizontal plane, a 25 display sheet mounted on said reels, a clutch located between said reel shafts, a transmitting shaft at each side of said clutch controlled thereby and occupying the space between said clutch and the reel shaft at that 30 side, means operatively connecting each of said transmission shafts with the adjacent reel shaft, a motor operatively connected with one of said transmission shafts, a screw shaft arranged parallel with said transmission shaft, means operatively connecting each 35 of said transmission shafts with said screw shaft, the means whereby one of said transmission shafts is operatively connected with said screw shaft causing a reverse relative 40 rotation between such transmission shaft and said screw shaft from the means operatively connecting the other transmission shaft with said screw shaft, a traveling member reciprocated by said screw shaft, and reversing 45 means for said clutch operatively connected with said traveling member.

2. In a display device, a flexible connection provided with matter to be displayed, a pair of reels on to which and off from which said 50 connection winds, operating mechanism for said reels comprising a line of shafting to rotate said reels, a motor to rotate said shafting, means operatively connecting said motor with said line of shafting, said means comprising a motion reversing device, said motion reversing device comprising a clutch for 55 said line of shafting, an oscillatory pivotally mounted cam plate having an operating arm which extends radially from its center of 60 oscillation, an operating lever for said cam, said lever being pivoted between its ends, one end portion of said lever being alternately engageable with opposite sides of said arm to move it in reverse directions, a spring carried 65 by said lever and having a lost motion con-

nection with said cam plate on the side thereof opposite to its radial arm, said spring being adapted to impart a reverse overthrow movement to said cam plate when the adjacent end of said lever moves over and beyond 70 the end of said operating arm, and means for rocking said operating lever in reverse directions.

3. In a device of the class described, a reciprocatory clutch-operating element, a rock shaft operatively connected with said element to reciprocate the same, a vertically disposed cam plate secured to said rock shaft, said cam plate having a segmental portion at one side of said rock shaft and an operating 75 arm projecting radially from the other side of said rock shaft, a screw-propelled reciprocatory member, guiding means for said member, a screw shaft to reciprocate said member, a lever positioned between said member and operating arm, a shaft whereon said lever is pivoted between its ends, one end of said lever being oscillated by said member and the other end of said lever sweeping back and forth across the free end of said arm, stop means to limit the movement of said arm, and an overthrow spring for said cam plate, said spring being secured to said lever.

4. In a device of the class described, a pair 90 of reels, a connection winding upon and unwinding from said reels, means for rotating said reels first in one direction and then the other, a clutch to reverse the direction of rotation of said reels, a reciprocatory clutch-operating element for said clutch, a rock 95 shaft operatively connected with said element to reciprocate the same, a cam plate secured to said rock shaft, said plate having an operating arm which extends therefrom in an edgewise manner and being provided with a cam edge at each side of said operating arm, a member constructed and arranged to move along one of said cam edges then across the free end of said operating arm and then across the other cam edge and against the 100 opposite side of said operating arm thus performing a like movement in the reverse direction, a spring carried by said member and arranged to give a reverse throw to said cam plate whenever said member clears the free end of its operating arm, and means to reciprocate said member.

5. In a device of the class described, a 115 motor, a primary shaft driven by said motor, a worm secured to said shaft, a worm gear wheel in mesh with said worm, a main transmission shaft to which said worm gear is secured, a continuously rotating clutch member driven by said main transmission shaft, 120 a pair of cooperating clutch members, the members of said pair being located on opposite sides of said continuously rotating clutch member, a secondary transmitting shaft connected to each of said cooperating clutch 125 members, a lever pivoted between its ends, one end portion of said lever being alternately engageable with opposite sides of said secondary transmitting shaft, a spring carried by 130 said lever and having a lost motion connection with said cam plate on the side thereof opposite to its radial arm, said spring being adapted to impart a reverse overthrow movement to said cam plate when the adjacent end of said lever moves over and beyond the end of said operating arm, and means for rocking said operating lever in reverse directions.

members, a reel operatively connected with each of said secondary transmitting shafts, a screw shaft operatively connected with said secondary transmitting shafts, a reciprocating member mounted on said screw shaft, 5 guiding means for said reciprocating member, said member having a pair of upstanding arms in spaced relation to each other, a lever pivotally mounted between its ends to oscillate in a vertical plane, the lower end of said lever being positioned with a part thereof between said arms to be oscillated by said reciprocating member, a cam plate located above said lever to oscillate in the same plane 10 therewith, said cam plate having an operating arm in position for the upper end of said lever to sweep back and forth across its free end to oscillate said cam plate, an over-throw spring for said cam plate, said spring 15 being secured to said lever and being adapted to give a reverse throw to said cam plate when the adjacent end of said lever clears the end of the operating arm of said cam plate, a shaft to which said cam plate is fixed and 20 which forms the pivot thereof, a crank arm carried by said shaft, means operated by said crank arm to alternately throw the above recited cooperating clutch members into engagement with the continuously rotating 25 clutch member, the last recited operation causing one of said reels to operate and simultaneously causing the other reel to stop, and vice versa, and a connection having its opposite end portions wound upon said reels 30 and being provided with matter to be displayed.

In testimony whereof I hereunto affix my signature.

JESSE V. MEISER.
